Attorney

UNITED STATES PATENT OFFICE.

CHARLES H. REED, OF SAN FRANCISCO, CALIFORNIA.

FINGERING ATTACHMENT FOR STRINGED INSTRUMENTS.

1,374,388.

Specification of Letters Patent. Patented Apr. 12, 1921.

Application filed June 14, 1918. Serial No. 239,922.

To all whom it may concern:

Be it known that I, CHARLES H. REED, citizen of the United States, residing at San Francisco, in the county of Alameda and State of California, have invented certain new and useful Improvements in Fingering Attachments for Stringed Instruments, of which the following is a specification.

10 This invention is an improved transposing keyboard for ukuleles, guitars, banjos, and similar stringed instruments.

The object of the invention is to provide a keyboard slidable on the neck of a stringed instrument and arranged to depress the strings against the frets by the use of keys, the heads of which are to enable one unskilled in music to follow a chart and render a composition of music.

20 This object is fully accomplished in the novel structure described in the following specification and illustrated in the accompanying drawing, in which—

Figure 1 is a top plan view of my improved keyboard.

25 Fig. 2 is an end view of same.

Fig. 3 is a longitudinal sectional view on the line 3—3 of Fig. 1.

30 Fig. 4 is a view of the end opposite that shown in Fig. 2, with a cover removed.

Fig. 5 is a side view of a cover.

Fig. 6 is an end view of same.

35 Fig. 7 is a perspective view of a guide grip.

Fig. 8 is a fragmentary view of an instrument with my improved keyboard in operative position thereon.

Fig. 9 is a detail showing the method of attachment to the instrument.

40 Fig. 10 is a bottom plan view of a key.

Referring to the drawings, A indicates a keyboard having sixteen circular holes a in its top for keys B. Both the keyboard and the keys are preferably made of celluloid or some suitable light material.

45 The keys B have enlarged heads C bearing numerals from 1 to 16 in the order shown in Fig. 1, and are also provided with collars or stops D. The keyboard A has 50 two similar mortises E on its nether surface to allow the keys to play vertically.

The keys 13 are normally held up by springs F coiled around the said keys and bearing at one end against the collars D and at the opposite end against a floor plate 55 G having holes, registering with those in

the keyboard A through which the keys B extend.

To prevent the keys from turning and reversing the numerals on their heads, I have 60 provided a rib H on the side of each key which extend through notches h in the side of the key holes a of the keyboard A.

In order to extend the foot of each key laterally of the strings of the instrument, I 65 have provided on the foot of each key a cross piece I extending beyond the diameter of the key.

On the bottom of the keyboard are legs J and a transverse bridge K, the legs J being 70 adapted to rest upon the finger board of the instrument between the strings thereof and the bridge K being at the upper end of the keyboard and adapted to extend across the 75 strings of the instrument and depress said strings upon the nearest fret of the instrument forwardly of the bridge. The bottom of the keys B, legs J and bridge K may be covered with felt or chamois skin.

80 The end of the keyboard carrying the foot K is provided with a mortise L as shown in Fig. 4. Slidable in the mortise L are four centering keepers M engaging and centering the strings of the instrument with relation 85 to the keys B.

The keepers M are spade shaped the handle portions adapted to slide in mortises L' and the opposite ends in mortises L''. They are prevented from coming out by 90 shoulders N.

The keepers M are normally depressed by coiled springs O surrounding the handle portions and bearing at the upper end against the upper wall of mortise L and at 95 the lower against the shoulders N.

The keepers M are formed with V-shaped notches P in their lower edges which are wide enough to engage the strings of the instrument at any point of the fingerboard of 100 the instrument to bring the strings under the keys B in central alinement therewith.

The mortise L is covered by an end piece Z of the size and shape of the end of the keyboard A as shown in Figs. 5 and 6.

105 In Figs. 8 and 9 I have shown a method of attaching my keyboard to an instrument Q. To one side wall of the keyboard A I attach one member R of a hinge, the other member S of which is curved to surround 110 the neck of an instrument. The end of member S opposite the hinge is provided with a

keyhole slot T for engaging a pin U in the side of the keyboard and opposite the hinge.

Near the center of the hinge member S are two holes through which extend pins V to the ends of which is attached a cushion W. The cushion W is normally pressed against the back of the neck of the instrument Q by springs X bearing at one end against the cushion and at the other against the member S. The pins V are slideable within the holes in the member S. This construction allows the keyboard to be slidably secured to the instrument.

What I claim as new and wish to secure 15 by Letters Patent is:—

1. A transposing keyboard having keys adapted when depressed to depress strings of a musical instrument having a neck against frets on said neck, said keyboard 20 being slideable on the neck of said instrument and yieldably secured thereto by a yoke hinged at one end to said keyboard and removably connected to the keyboard at the opposite end of said yoke, said keyboard 25 being provided with a plurality of centering keepers adapted to keep the strings in alignment with said keys, said keepers being

normally depressed by coiled springs surrounding portions thereof.

2. A fingering attachment for stringed 3 musical instruments having a neck including a transposing keyboard, means for attaching the keyboard to the neck of the instrument, keys on said keyboard for engaging the strings of the instrument, centering keepers 31 yieldingly mounted in the keyboard and provided with notches in their lower edges to receive and center the strings with relation to the keys.

3. A fingering attachment for stringed 40 musical instruments having a neck including a transposing keyboard, means for attaching the keyboard to the neck of the instrument, keys mounted in said keyboard for depressing the strings of the instrument, centering 45 keepers slidably mounted in said keyboard for engaging and centering the strings with relation to the keys, springs for forcing the keepers into engagement with the strings, and shoulders on the keepers for engaging a 50 part of the keyboard for limiting the outward movement of the keepers.

In testimony whereof I affix my signature.

CHARLES H. REED.
